UNITED STATES PATENT OFFICE

2,358,436

CARPET STRETCHER

Justin D. Bartlow, Long Beach, Calif., assignor
to Jesse C. Owens

Application May 18, 1943, Serial No. 487,480

11 Claims. (Cl. 254—62)

My invention relates to carpet stretchers of the particular type covered by U. S. Letters Patent No. 1,766,423 issued to me June 24, 1930, also Letters Patent No. 2,103,506 issued to John C. Owens, February 15, 1938, also Patent No. 2,326,117 issued to me August 10, 1943, of which, this application is a continuation in part.

The principal objects of my invention are, to generally improve and simplify the constructions disclosed in the aforesaid patents, to provide improved means for imparting forward movement to the carpet engaging head of the device during stretching operations, to provide simple and efficient means for maintaining the body of the stretcher in extended position to facilitate the stretching and tacking operations and further, to provide simple and efficient means for releasably connecting the telescoping parts of the body of the stretcher.

With the foregoing and other objects in view, my invention consists in certain novel features of construction and arrangement of parts which will be hereinafter more fully described and claimed and illustrated in the accompanying drawings in which:

Fig. 1 is a top plan view of a carpet stretcher constructed in accordance with my invention, with the head that carries the carpet engaging prongs in horizontal section.

Fig. 2 is a side elevational view of the stretcher with the head in vertical section.

Fig. 3 is an enlarged horizontal section taken on the line 3—3 of Fig. 2.

Fig. 4 is a cross section taken on the line 4—4 of Fig. 1.

Fig. 5 is a perspective view of a sliding pivot block used in the main frame of the stretcher.

Fig. 6 is a vertical section taken on the line 6—6 of Fig. 1 and showing the telescopic member latching means.

Fig. 7 is an enlarged cross section taken on the line 7—7 of Fig. 1.

Fig. 8 is a plan view of a modified form of the stretcher with parts at the ends broken away.

Fig. 9 is a longitudinal section taken on the line 9—9 of Fig. 8.

Fig. 10 is a cross section taken on the line 10—10 of Fig. 9.

Fig. 11 is a horizontal section of the telescopic members and showing a latch therefor.

Fig. 12 is a horizontal section showing a modified form of the latch for the telescopic members.

Fig. 13 is a horizontal section showing a further modified form of the latch.

Referring by numerals to the accompanying drawings, particularly the construction illustrated in Figs. 1 to 7 inclusive, 10 designates a tube which may be of any desired and convenient length, and arranged to telescope said tube is a slightly smaller tube 11, to the outer end of which is connected by vertical pivot 12 a block 13 that is adapted to bear against the base board or wall of the room in which the carpet stretcher 10 is used.

To maintain the tubes 10 and 11 in their different telescopic adjustments, a U-shaped spring is positioned within the smaller tube 11 and projecting in opposite directions from the 15 ends of the legs of said spring are studs 10a which pass through apertures 11a in tube 11 and the projecting portions of said studs are adapted to enter apertures 10b that are formed in the outer tube 10.

20 The apertures 10b are countersunk in order that the projecting ends of the studs 10a may be readily engaged and pressed inwardly by the thumb and finger so as to enable the tubes to be moved longitudinally independently of each 25 other.

The forward end of tube 10 is secured in any suitable manner to a lug 14 that is formed on the rear end of a frame that comprises a pair of parallel channel bars 15 arranged with their 30 flanges inwardly presented and the rear ends of said channel bars being integrally connected by a cross piece 16. A cross piece 17 is formed integral with and connects the forward portions of the channel bars 15.

35 Arranged for sliding movement against the inner faces of the webs of the channel bars 15 between the flanges thereof are parallel bars 18 and the forward ends of these bars are rigidly connected to the main body or housing 19 of a 40 head, which housing is substantially rectangular in form and provided with an open bottom.

Arranged to slide freely lengthwise between those portions of the bars 18 that extend into the frame comprising the channels 15 and supported by the inner portions of the lower flanges on said channel bars 15 is a block 20, the forward portion of which is provided with a vertically disposed slot 21. Projecting upwardly from the forward portions of the walls to the sides of 45 slot 21 are ears 22 provided with apertures 23.

Passing through the apertures 23 is a transversely disposed pin or bolt 24 and mounted on the ends thereof that project beyond the ears 22 are rollers 25 that bear on the upper surfaces 50 of the channel bars 15.

Fulcrumed on pin 24 between the ears 22 is the forward portion of a longitudinally disposed lever 26, said forward portion being curved slightly upward and secured to the rear end of this lever is a rearwardly projecting handle 27.

A link 28 has one end pivotally connected to the forward end of lever 26 a short distance in front of its fulcrum, the pin 24, and the lower forward end of this link being pivotally connected to a transversely disposed pin 29 that is seated in the forward portions of bars 18.

Pivotally connected by means of a pin 30 to lever 26 a short distance rearwardly from the fulcrum 24 are the forward ends of parallel links 31, the same extending between the channel bars 15 and having their rear ends pivotally connected to a transversely disposed pin 32 that is seated in the rear portions of said channel bars.

Arranged for vertical movement within housing 19 is a plate 33 in which is seated the upper ends of a series of downwardly and forwardly projecting prongs 34 that are adapted to engage the carpet that is being stretched by the device, and extending lengthwise through the center of the housing above this plate 33 is a shaft 35, the ends thereof being mounted for rotation in bearings formed in the end walls of housing 19.

One end of this shaft 35 is enlarged in diameter as designated by 36 and a tubular bearing 37 on the end wall of the housing surrounds this enlarged portion.

Arranged for sliding movement in the enlarged end portion 36 of the shaft is a diametrically arranged spring pressed pin 38, the outer end of which is adapted to enter any one of a series of apertures 39 that are formed through the wall of the bearing 37, thus maintaining the shaft 35 at different points in its rotation.

The apertures 39 in the bearing 37 are countersunk in order that the end of the pin may be engaged and pressed inward when it is desired to partially rotate and adjust the position of shaft 35. The apertures 39 are spaced apart circumferentially of the bearing.

Formed in the outer end of the enlarged end portion 36 of the shaft is a slot 40 for the reception of a screw driver or suitable tool used in imparting rotary motion to the shaft.

Secured to shaft 35 within housing 19 adjacent the ends thereof are eccentric discs 41 and formed in each disc is an arcuate slot 42 that extends from a point near the edge of the disc to a point near the axis thereof, the shaft 35, and secured to and projecting upwardly from the prong carrying plate 33 are pairs of ears 43 and passing therethrough and through the slots 42 are pins 44. The construction just described provides means for positively raising and lowering the prong carrying plate.

Suitably secured by rivets 45 or otherwise to the top of housing 19 adjacent the eccentrics 41 are the central portions of inverted U-shaped springs 46, the lower upturned ends of which bear directly upon the upper surface of the prong carrying plate 33 so as to yieldingly oppose the upward movement thereof into the housing 19, and such action cooperating with the connection between the discs 41 and plate 33 in maintaining the latter at different elevations.

In the operation of the form of carpet stretcher just described, one edge of the carpet is tacked to the floor adjacent the base board and the stretcher is now positioned on the carpet with the block 13 bearing against the base board or

wall adjacent the edge of the carpet that has been secured to the floor and with the head of the stretcher, the housing 19, positioned on top of the carpet adjacent the wall opposite the wall against which block 13 is positioned.

Before beginning the stretching operation, the hand lever 27 is swung upwardly and forwardly into a substantially vertical position as illustrated by dotted lines in Fig. 2 and under such conditions the head of the stretcher is positioned immediately adjacent the forward end of the frame comprising the channel bars 15, and the links 28 and 31 occupy positions as illustrated by dotted lines in Fig. 2.

If the carpet that is being laid is thick or has a heavy nap, then the shaft 35 is rotated so that through the action of the slots 42 and pins 44 the plate 33 is moved to its lowermost position within the housing 19 so that the prongs 34 will project entirely through the thick carpet. If, however, the carpet is comparatively thin or of medium thickness, then the shaft 35 is rotated so as to partially or fully elevate the prong-carrying plate 33, as the case may be, thus varying the distance that the points of the prongs extend below the under face of the housing 19.

In laying the stretcher on the floor, it will be understood that the rods 10 and 11 are telescopically adjusted so as to position the head of the stretcher on the free edge of the carpet and such lengthwise adjustment is attained by first disengaging the studs 10a from the apertures 10b in tube 10, then moving the tube longitudinally with respect to each other, and at the termination of such adjustment the tubes are secured against further longitudinal movement by the engagement of the studs 10a in another set of the apertures 10b.

After the prongs have been engaged in the carpet a short distance inwardly from the free edge thereof, the operator swings handle 27 from its vertical position rearwardly and downwardly to the position shown by solid lines in Fig. 2, which action swings the forward portions of the links 31 into a position between the parallel members 15 of the frame, and the link 28 that is connected to the forward end of the handle and to the bars 18 will be swung upward into the position shown by solid lines in Fig. 2, and as a result of those movements the bars 18 carrying the head of the stretcher will be moved forwardly from the forward ends of the frame comprising the parallel bars 15 and thereby correspondingly stretch or move the carpet from the edge that is secured to the floor.

The operations just described, namely, the longitudinal adjustment of the tubes 10 and 11 and the retraction and subsequent forward projection of the head of the stretcher by manipulation of the handle 27, are repeated until the carpet has been properly stretched and the free edge thereof is brought into position adjacent the base board of the wall opposite the wall against which block 13 bears and the free edge of the carpet may now be secured to the floor in the usual manner.

It is to be noted that the pivot 32 between the rear ends of the links 31 and the frame of the stretcher and the pivot 29 between the forward end of link 28 and the bars 18, occupy a horizontal position wholly below the axis 24 of handle 23 and likewise below the pivotal connection 30 and the point of pivotal connection between link 38 and the forward end of lever

26 that forms a part of the handle, and as a result of this arrangement, when the handle is swung downward to its limit of movement as illustrated by solid lines in Fig. 2, the handle and links are locked in such position due to the past or below center positions of the pivots 29 and 32.

During the swing of the handle 27 from one position to another, block 20 that provides a fulcrum for the handle slides freely between the rear portions of bars 18 and the rollers 25 carried by the ends of fulcrum pin 24 roll on top of the upper flanges of the channel bars 15, thereby materially reducing friction of the cooperating parts while in action.

In the modified construction illustrated in Figs. 8 to 13 inclusive, a pair of channel bars 50 are secured to and project rearwardly from the prong carrying head 51 and arranged to slide freely through a bearing 52, formed between said bars is a tube 53. This tube 53 is the outer one of two or more telescopically associated tubes, practically identical with the telescopic tubes 10, 11, 12 and 13 shown in my Patent No. 1,766,423 and the inner one of the tubes in the present case, carrying at its outer end a block (not shown) similar to block 17 in said patent.

Numerical 54 designates a tube which is arranged to slide within tube 53. These telescopic tubes may be latched to each other after relative longitudinal adjustment in various ways, for instance, by means of pins 55 carried on the ends of a bow spring 56, the latter positioned in tube 54 and which pins engage in apertures formed in the tubes. These apertures may be lined with rings or collars 57 preferably of hard wear resisting metal (see Fig. 11), such construction being especially desirable where the tubes are formed of plastics or composition.

In Fig. 12, the telescopic tubes 58 and 59 are shown as being substantially oval in cross section and provided on top with upstanding flanges 60.

Arranged within the inner tube 59 is a transversely disposed spring pressed extensible latch pin 61, the ends of which are adapted to engage in coinciding apertures formed in the sides of the tubes.

In Fig. 13 the latch consists of a disc 62 having bearings in the outer tube 63 and extending through slots in the inner tube 64, and formed in said disc are oppositely arranged arcuate slots 65.

Passing through said slots are pins 66 seated in the inner ends of pins 67, and the latter being adapted to engage in coinciding apertures formed in the tubes and said apertures being reinforced with hard metal rings 68.

A bow spring 69 has its ends seated in pins 67 so as to yieldingly resist inward movement of said pins.

Arranged to move freely between the forward portions of the channel bars 50 is a fulcrum block 70 and mounted for operation in anti-friction bearings 74 therein, are the axes 72 of rollers 73 which bear on the lower flanges of the bars 50.

Block 70 is provided with ducts 74a whereby the axes 73 may be lubricated.

Projecting upwardly from one end of block 70 are ears 75 in which is seated a pin 76 providing a fulcrum for a hand lever 77, which occupies a lengthwise position above the bars 50.

The forward end of lever 77 which extends a short distance forwardly of fulcrum 76 is connected to body 51 by a link 78. The rear end

5 of link 78 is connected by a pivot pin 80 to the forward end of tube 53 and the forward end of said link is pivotally connected to lever 77 a short distance to the rear of fulcrum 76. When hand lever 77 occupies its lowermost position against the bars 50 as seen in Fig. 9, the axis of pin 81 is "past center" or a short distance below the plane occupied by the pivot pins 76 and 80 and thus the stretcher is practically locked against retraction until the handle is raised a sufficient distance to position pin 81 above the plane occupied by pins 76 and 80.

10 Fulcrum block moves freely forwardly or rearwardly to accommodate itself to the movements and positions of hand lever 77 and when said lever is drawn upwardly, the prong-carrying head 51 and bars 50 will be drawn rearwardly and at the same time, tube 53 will be drawn forwardly, or if the block on the rear end of the telescopic tubes is held against a wall, the channel bars 50 and head 51 will move a considerable distance rearwardly on the forward portion of tube 53.

Runners 82 are positioned on the under sides of bars 50, to the rear of head 51, thus enabling said head and bars to slide freely on the carpet and provide a guard to prevent the connected ends of hand lever 77 and link 78 from contacting the carpet during stretching operations.

Thus it will be seen that I have provided a 15 carpet stretcher which is simple in structure, inexpensive of manufacture and very effective in performing the functions for which it is intended.

It will be understood that minor changes in the size, form and construction of the various 20 parts of my improved carpet stretcher may be made and substituted for those herein shown and described without departing from the spirit of my invention, the scope of which is set forth in the appended claims.

40 I claim as my invention:

1. In a carpet stretcher, a frame, an extensible member connected to one end of the frame, a housing mounted on the opposite end of said frame, a prong carrying member within said housing, adjustable means within said housing for regulating the effective length of the prongs carried by said member, a handle having a fulcrum on said frame and links associated with said handle and pivotally connected to said frame and said housing with the points of pivotal connection between said links, said frame and said housing, occupying a horizontal position below the fulcrum of the handle when the same is swung downward into position immediately adjacent said frame and extensible member.

50 55 2. A carpet stretcher as set forth in claim 1 and with anti-friction rollers carried by said handle and bearing on top of said frame.

3. In a carpet stretcher, a frame, an extensible member connected to one end of said frame, a housing mounted on the opposite end of said frame, a prong carrying member within said housing, adjustable means within said housing for regulating the effective length of the prongs carried by said member, a handle having a fulcrum on said frame, links having their inner ends pivotally connected to said handle on opposite sides of its fulcrum and the outer ends of said links being pivotally connected respectively to said frame and said housing in a horizontal plane below that occupied by the fulcrum of the handle.

70 75 4. A carpet stretcher as set forth in claim 3 and with anti-friction rollers carried by said handle and bearing on said frame.

5. In a carpet stretcher, a frame, an extensible member connected to one end of said frame, a housing mounted on the opposite end of said frame, a prong carrying member within said housing, adjustable means within said housing for regulating the effective length of the prongs carried by said member, a handle, a fulcrum for said handle, which handle is mounted for longitudinal sliding movement on said frame, links having their inner ends pivotally connected to said handle on opposite sides of said sliding fulcrum and the outer ends of said links being pivotally connected respectively to said frame and housing in a horizontal plane below that occupied by the fulcrum of the handle.

6. A carpet stretcher as set forth in claim 5 and with rollers carried by said sliding fulcrum and arranged to bear on said frame.

7. In a carpet stretcher, the combination with an extensible member and manually operable means for imparting extensible movement thereto, of a housing carried by the forward end of said member, a prong carrying plate arranged for vertical movement within said housing, a shaft 20 passing through said housing above the prong carrying member, eccentric discs carried by said shaft, pin and slot connections between said prong carrying member and said discs and means

within the housing for yieldingly resisting the upward movement of the prong carrying member therein.

8. In a carpet stretcher, the combination as set forth in claim 7 and with means for securing said shaft at different points in its rotation.

9. In a carpet stretcher, a frame, an extensible member having one end arranged for sliding movement in said frame, a prong carrying head on the forward end of said frame, a block arranged for sliding movement in said frame, anti-friction means between said block and frame, a hand lever fulcrumed on said block and links pivotally connecting said hand lever with said head and with said extensible member.

10. A carpet stretcher as set forth in claim 9 and the point of pivotal connection between said extensible member and the link connecting same to said lever and the fulcrum of said lever occupying a plane above that occupied by the pivotal point between said lever and the link which connects same to the extensible member, when said lever is at the lower end of its travel.

11. A carpet stretcher as set forth in claim 9 and with a runner on the under side of said frame to the rear of said prong carrying head.

JUSTIN D. BARTLOW.
